UNITED STATES PATENT OFFICE.

EDWIN L. GRAUEL, OF CINCINNATI, OHIO, ASSIGNOR TO THE GRAULCCK COMPANY, OF CINCINNATI, OHIO, A CORPORATION OF OHIO.

LOCKING-DEVICE CONTROL.

Application filed September 6, 1923. Serial No. 661,276.

My invention relates to locking devices which are to be operated electrically, and to the application of such locking devices to motor vehicles in particular.

5 In my former application for Letters Patent, Serial No. 599,068, filed November 4, 1922, I have set forth and described a mechanism and schematic principle for use in locking device controls, and the present invention is related to the same subject matter.

Briefly reviewing the object of the former invention and the present invention, where in common with each other, it is the provision of a locking device control which comes 15 into operation to inhibit the use of a desired mechanism, such as an automobile engine, upon the manipulation or other movement of a member which is normally energized as a necessary step in connection 20 with the said mechanism. The object is also to associate with such a control, a key or combination lock which must be when in position after having released the inhibitory device, so set that upon the next energization 25 of the necessary member, the inhibition will again come into effect.

As in my former device, the present invention uses, as a particular means of making the inhibition a safe one, a spring controlled member, electrically energized, which when released will move to inhibiting position, so that to cut the electrical connections, will not avoid the inhibition. Also I use as 30 my electrical circuit a cable in which a number of wires are packed, some of which wires are used in the circuit, but most of which are inserted to greatly increase the difficulty of 35 an unauthorized person testing out the wires which are in fact connected to the apparatus.

40 The essential difference between the present invention and the one above referred to, is that in enforcing a setting of the lock element for running, at the same position which will give locked position, say, upon 45 the throwing off of the ignition, I employ a mechanical trigger, instead of using an electrically locked up circuit.

To explain this more clearly, the inhibiting device in one form of the invention is a 50 valve to prevent entrance of motive fuel to the engine, the direct control is an electro-magnet which when energized will remove the valve from fuel blocking position. The necessary element of the mechanism which

acts as energizer for the control, is the ignition circuit and switch, since the switch must be opened to stop the engine, and closed to start it. The lock is a switch protected by a combination device, or by a necessary key operation.

In my former device as in the present device I used two electro-magnets which had to be operated in a definite series. The circuits from the lock to the magnets were as 65 here enclosed in a cable "camouflaged" with a large number of extra shorted or open wires.

In the former device the lock first closed the armature of one of the electro-magnets, 70 acting as a relay, which was required to form the circuit, for the valve controlling electro-magnet, said last named circuit being established by a further movement of the lock device. Thus when releasing the ignition switch after the full operation of the lock, 75 the valve would drop to closed position, and could not be opened until the lock had been moved through its sequence.

In the present case, instead of using the 80 relay, I employ a special armature for the valve controlling electro-magnet, which armature cannot move because of a latch, which is formed on the armature of the first electro-magnet. Thus in this case the preparatory step must be followed, as before, 85 but its work is done through a latch, and not an electric circuit. This saves electrical work and labor cost, and the great disadvantage of moving contacts.

As will be noted, I provide a slow release 90 magnet for the latch, and also I provide for a specific preferred way of inhibiting the fuel flow, which is so arranged that even after the vehicle ignition has been shut off, 95 so long as the engine keeps turning over, the inhibiting valve will float in a partially open position, and the latch device will not drop in.

I have not shown the mechanical details 100 fully in the switch locks illustrated in the drawings, but have endeavored to show merely the principles of operation, as only in certain particular points is the design of importance in this invention. Thus among 105 other things, I show the ignition switch itself as the magnet circuit control.

I accomplish the objects above set forth and various other advantages to be noted by

that certain construction and arrangement of parts to be hereinafter more specifically pointed out and claimed.

In the drawings:

5 Figure 1 is a diagrammatic view of the device as applied to an automobile, showing the same in inhibiting position.

10 Figure 2 is a like view showing the result of operating the combination lock without moving the ignition switch.

15 Figure 3 shows a like view in which the ignition switch has moved through its first step of movement, the preparatory position.

20 Figure 4 shows the ignition switch moved to its full "on" position to the inhibition release position.

25 Figures 5, 6, 7 and 8 show the same four steps in operation as applied to a key lock, and of both sets, it is to be noted that the 20 final movement of throwing off the ignition switch will bring the parts back to the position of Figures 1 and 5 respectively.

30 Figure 9 is a face view of the key lock device.

35 Figure 10 is a diagram of the "camouflaged" circuits used.

40 Figure 11 is a diagram of the action of manifold currents on the inhibiting valves of engines.

45 Referring to the drawings, the part illustrated at 1 is the manifold end of a carburetor, and the part at 2 is the meeting portion of the manifold, these two parts being secured together in some desired way 50 so as to defy a speedy separation. As a general objective in this juncture of elements, it is my desire that it be made harder to get the two flanged connections at 1 and 2 open, than to take off the entire manifold and carburetor.

55 Secured in the filler piece 3, that is secured between the parts 1 and 2 is a nipple or sleeve 4, which is a part of some sort of inaccessible casing, that surrounds the electromagnets and armatures. I have not shown such a casing, as this will be varied to suit the desires of the manufacturer. Of this method of arranging the lock it 60 should be noted that it will be almost universally applicable to all vehicles in a common design.

65 The valve 5 is pivoted in the filler piece 3, and has an arm 6 thereon which is linked by the spring plunger 7 with the electric mechanism. The spring 8 surrounds the plunger, and tends to force it to position to close the valve. The diagram in Figure 11 shows a pipe A, with a valve B and B¹, mounted in the center, a valve C, and C¹ mounted to one side of the center, and a valve D and D¹ mounted to the other side of the center. The valve B, B¹ will preferably be the one used.

70 85 The valves C, C¹, as illustrated by the small arrows, stay open, so long as currents

are flowing through the pipe A. This is partially true of valve C, C¹, which is my preferred form. The arrows at B¹ show how the air currents tend to deflect toward the opening exposed by the valve nearest the engine, but when the valve is closed they tend to keep it closed. The valve D, D¹ is only slightly off center, and while it will tend to be closed, still when open, the slippage of air currents will hold it balanced in position, as indicated by the arrows impinging on D¹.

75 Furthermore when the engine is shut off, the action is to continue to suck through the manifold until the last turn over of the fly-wheel, whereupon there is a compression in one cylinder, which the fly-wheel cannot overcome. This compression affects the manifold by a slight blowing back through the same, thereby tending strongly to close 85 the valve such as at C, C¹, and also tending to close the valve at B, B¹, only not so much so.

80 I find in fact that the spring device on the plunger is not really necessary, because 90 of this closing automatically of the inhibiting valve under the back pressure now described.

85 The electro-magnets are shown at 9 and 10, of which 9 is the preparatory magnet, 95 and is quick acting, slow release design, (a familiar relay construction), and 10 is the valve operating magnet. The armature 11 is connected to the plunger 7, and is drawn to the magnet 10 when current is passed 100 through its coils. The armature 12, which is drawn to the magnet 9 when the same is energized, is pressed by a spring 13, so that it acts as a spring latch. When the armature 11 is in position which it assumes with 105 the valve closed, the arm 12^a on this armature 12 will be so placed as to prevent movement of 11 toward valve opening positions (Figures 1 and 2). The armature 11 has a hole in it at 14, however, which clears 110 the arm 12^a of the armature 12, when said armature has been attracted to the magnet 9.

115 Thus the sequence of operation is to energize magnet 9, which will comparatively draw out of the way the latch armature thereof, and then slowly release it, and during this release to operate the magnet 10, resulting in movement of its armature, now freed for movement to open the valve.

120 As will be noted, the act of turning off the ignition not only takes the current away from the magnet 10, and releases the armature 12, but the armature is then latched against operation, so that turning on the 125 ignition will not re-open the valve, unless the lock is first manipulated.

130 However, if air currents are moving through the manifold, and the ignition switch is turned off, the valve does not move

fully back, but stays in the position to hold the parts, as illustrated in dotted lines at Figure 4, so that the re-closing of the ignition switch will preserve the open position 5 of the valve. This will be further explained, after a description of the circuits. In Figures 1 to 4, I have shown partially diagrammatic views of a combination plunger controlled lock, in which there is a 10 lock plate 20, the movement of which is prevented by plungers 21. A proper setting of the plungers will, however, permit the plate to be moved by a spring 22, in a slight rotary movement. The selected disk is 15 mounted on a spindle 23, which also carries the operating handle 24 of the ignition switch. The disk has a pin, however, as at 25, which engages in a slot within the handle 24. The disk springs to one circuit establishing position and is moved by the full throw of the ignition switch to its other circuit establishing position.

I have illustrated the disk as having a contact arm 26, and have shown a contact 25 27 to the ground, and a contact 28 in the circuit of the magnet 9. Also I show a contact 29 in the circuit of both magnets. The magnet 9 is connected by wire 28^a to the contact 28, and magnets 9 and 10 have 30 leads to the wire 29^a to the contact 29. The other end of the coil of magnet 9 is connected to the ground.

I have shown the ignition switch as having two terminals, one of which at 30 is 35 connected to the terminal 28, and the other of which at 31 is connected to the battery 32, and thence to the ground. The ignition circuit itself employs the connecting lead 33 between the terminal 30 and the terminal 28, 40 and is indicated at 34.

Terminals 31 and 29 are longer than the others, as will be noted, resulting in the following operation. Upon the release of the combination lock plate, it will spring 45 of itself to a position of bridging, by means of the contact arm 26, the terminals 28 and 29, (Figure 2). The operator then starts to close his ignition switch, with the result of first connecting terminals 30 and 31, and sending a current from the battery through terminal 28, through the magnet and back through terminal 28 and to the ground, thereby energizing magnet 9 (Figure 3). At this time the ignition circuit will 50 be closed also.

The continued movement of the switch handle will cause it to pick up the pin on the lock disk, and to throw over the lock disk to locked position, bridging the terminals 28 and 29, and thus by-passing magnet 9, and sending current through terminal 28 to terminal 29, thence through magnet 10, and to the ground from said magnet. This 55 operates the valves moving armature, and since the magnet 9 releases in a retarded

manner, the trigger or latch will be in position at the time that the armature 12 is operated to free it for operation. (See Figure 4 for this position).

When later the operator stops his motor 70 by throwing down the ignition switch handle, he opens the circuit to magnet 10, latch 9 falls in position and the location of parts will be as in Figure 1.

I have shown in Figure 10 the method of 75 "camouflaging" the circuit noted, namely by packing in with enamel coated wires for the circuits noted additional wires as at 35, which are connected at their ends within the inaccessible casing, so as to establish connections of two, three, and any kind of desired shorts, whereby the thief when testing for circuits among the wires, will never be able to tell whether he has an operative wire or an inoperative one. Thus if he withdraws one wire from the bundle and tests it with the rest of the bundle as a mass, and finds a short, he will not be able to tell that he has picked up one of the real circuits or one of the "fake" circuits. 80 85 90

As to simplicity for the operator, there is but one complication, namely: he must operate the combination lock before he can run his car. The sequence of operations of lock and switch are enforced on the operator, 95 because if he should throw on his ignition first he cannot throw the handle clear over until the lock is released. The lock will always set when the ignition is off the car, however, but if the operator accidentally or 100 thoughtlessly strikes over the ignition switch handle, he can catch himself up before the engine stops turning without having to work the lock again. It is believed that even under un-nerving conditions the 105 driver can tell at once if his ignition is off, and the engine ceases firing.

In case of the key lock, the enforcement for preserving the lock in condition to inhibit movement of the car when the ignition is off, is twofold. In the first place the key physically interferes with movement of the switch handle to off position, and in the next place the lock ejects the key automatically as soon as it is released from the 110 115 hand.

I have illustrated a portion of an inaccessible casing 40 to be mounted on the dash of a vehicle or elsewhere, in which is a lock formed of rocking spring-pressed plate 120 41. These plates are controlled by a key 49 to line them up with the notches 43 therein in line, so as to permit a switch bar 44 to fall into the lined up notches.

The ignition switch is formed with a handle 45 which when the switch is open lies across the key hole 46 to the lock. I have indicated that one of the ignition circuit wires 47 is connected to the switch handle, 125 and have indicated a spring contact 48 which 130

the handle will wipe over when it has been thrown to one side.

The contacts of the circuit mechanism, I have numbered the same as in the first instance. The terminal 28 is the movable one. The terminal 27 to the ground is below it, and the terminal 29 to the two magnets is above.

Normally the device is in the position of Figure 5 when the ignition switch is off. The operator in starting his car first throws the ignition handle over to the position shown in Figure 6 which connects battery with terminal 29 and 28, which is held in normal contact therewith. The operator then thrusts in the key 49 moving the lock plates until the switch bar falls carrying the contact 28 into contact with the ground 27. This sets up the circuit through the magnet 9, as in Figure 2. He then releases the key so that the lock plates swing outwardly under their own springs, ejecting the key and forcing the switch arm into a position to establish the contact at 29 again. This contact is now effective because the armature latch has been raised and the valve armature can then move over to valve opening position.

The next time the ignition switch is turned off, taking a current away from 29 and 28, the valve will close, and the latch armature will swing down to latching position. The valve armature cannot move again, until the magnet 9 has again been operated. The particular lock shown is detailed in my application Serial No. 618,205, filed February 10, 1923.

There are a wide variety of circuits that can be used in such a mechanism, but the one I have shown when properly "camouflaged" will thwart any attempts to test it out and operate it, short of enough time to take the entire carburetor off and manifold off and replace them with another.

A valve set into the manifold as I have shown, will block any attempts to operate the car.

It may thus be seen that the present invention differs in operative details from that shown in my former application first above referred to, in the magnet coil arrangements, in the circuit duplication which is avoided, and also the use of moving contacts, and in the confining of manipulated elements to the ignition switch and the lock. The particular combination lock device shown apart from its generic features forms part of another application for patent.

Having thus described my invention, what I claim as new and desire to secure by Letters Patent, is:—

1. In combination with an operation inhibiting mechanism, of electro-magnetic means controlling the same, and comprising a plurality of electro-magnets, armatures

for said magnets, and inter-related locking mechanism between said armatures, said locking mechanism being arranged to require operation of one armature to set the device, and subsequent operation of the other to release the inhibiting mechanism.

2. In combination with an operation inhibiting mechanism, of electro-magnetic means controlling the same, and comprising a plurality of electro-magnets, armatures for said magnets, and inter-related locking mechanism between said armatures, said locking mechanism being arranged to require operation of one armature to set the device, and subsequent operation of the other to release the inhibiting mechanism, one of the said armatures being directly connected to the inhibiting mechanism.

3. In combination with an ignition switch, a lock, electric circuits controlled by the switch and the lock, a driving inhibiting device comprising a pair at least of mechanisms energized by currents established by said circuits, and means whereby the lock operation establishes one of the circuits, and the switch operation establishes the other of the circuits for said pair.

4. In combination a pair of electro-magnetic devices for controlling a mechanism inhibiting device, a movable member requiring operation to stop and start the mechanism irrespective of the inhibiting device, a lock, and means requiring both an operation of the lock and an operation of the movable member in order to release the inhibiting device, and means for enforcing a locked position of the lock whenever the movable member is in stop position.

5. In combination a mechanism inhibiting device, an ignition switch and circuit for the mechanism, said inhibiting device being operated by the current passing through the ignition switch, and a switch device for the inhibiting device, said latter switch device comprising a lock controlled member, and a member controlled by the movement of the ignition switch.

6. A mechanism for operating a mechanism inhibiting device comprising a pair of electro-magnets, an armature for one of said magnets adapted to operate the inhibiting device, an armature for the other electro-magnet adapted to block the first armature from movement to non-inhibiting position, and to release it for operation when energized, and means for passing current through the said electro-magnets.

7. A mechanism for operating a mechanism inhibiting device comprising a pair of electro-magnets, an armature for one of said magnets adapted to operate the inhibiting device, an armature for the other electro-magnet adapted to block the first armature from movement to non-inhibiting position, and to release it for operation when ener-

gized, and means for passing current through the said electro-magnets, the magnet operating the armature secondly mentioned having a retarded releasing action, for the 5 purpose described.

8. An inhibiting device for mechanisms, comprising an ignition switch, a pair at least of electric circuits necessary to be closed and opened in a definite order, a lock device for 10 controlling said pair of electric circuits, and the ignition switch by its movement effecting at least one of the movements necessary in the closing of said circuits in the required order.

15 9. An inhibiting device for mechanisms comprising an ignition switch for establishing an ignition circuit for the mechanism, and a pair at least of electrically operated devices for controlling the release of the inhibiting device, each of same requiring the 20 separate closing of an electric circuit, contacts to be bridged in closing said circuits, said ignition switch having means for controlling the bridging of one of said set of 25 contacts.

10. An inhibiting device for internal combustion engines comprising a valve mounted in the manifold end of the carburetor, electro-magnetic means for moving said valve 30 to passage opening position, said valve being so mounted that upon release of the electro-magnet means it will not move to passage closing position until the engine has ceased its revolutions, and means for blocking the 35 movement of the valve to passage opening position until the electro-magnetic means has been operated.

11. An inhibiting device for internal combustion engines comprising a valve mounted 40 in the manifold end of the carburetor, electro-magnetic means for moving said valve to passage closing position, a spring for moving said valve to passage closing position, upon release of the electro-magnetic 45 means, said spring having insufficient power to move the valve to closing position until the engine has ceased its revolutions, and a latch forming part of said electro-magnetic means for blocking the movement of the 50 valve to opening position until said electro-magnetic means is fully operated.

12. An inhibiting device for internal combustion engines, comprising a valve mounted in the manifold end of the carburetor, electro-magnetic means for moving said valve 55 to passage opening position, said valve being so mounted that upon release of the electro-

magnetic means it will not move to passage closing position until the engine has ceased its revolutions, said electro-magnetic means 60 comprising at least two electro-magnets both of which must be operated before the said valve can move to passage opening position.

13. An inhibiting device for internal combustion engines, comprising a valve mounted 65 in the manifold end of the carburetor, means for moving said valve to passage opening position, means for moving the valve to passage closing position when the first mentioned means is out of operation, said last 70 named means being insufficient for moving the valve to passage closing position until the engine has ceased its revolutions.

14. An automobile locking device comprising a valve located in the manifold of 75 the automobile engine, said valve being arranged off center so as to tend to open with the suction in the manifold and tend to stay open until the suction ceases, an electro-magnetic latch, preventing the opening of 80 the valve once it is closed, an electromagnetic means for holding the valve open once it is open, means for applying closing force to the valve, and a necessary driving element 85 of the vehicle, controlled by the operator thereof, and the movement of which to stopping position is so arranged as to release the second noted electromagnetic means, thereby permitting the valve to close when the suction dies down.

15. A locking device for a vehicle having an engine for driving the same, means for preventing the vehicle from being driven, a lock controlled member adapted when the lock is closed to latch the said means in position for preventing the vehicle from being driven, and means whereby the first mentioned means is held in position permitting the vehicle to be operated so long as the 90 engine of the vehicle is in operation.

16. A locking device for a vehicle having an engine for driving the same, means for preventing the vehicle from being driven, a lock controlled member adapted when the lock is closed to latch the said means in 95 position for preventing the vehicle from being driven, and means whereby the first mentioned means is held in position permitting the vehicle to be operated so long as the engine of the vehicle is in operation, 100 said first mentioned means comprising a 105 valve pivoted off center in the fuel intake of the engine.

EDWIN L. GRAUEL.
